UNITED STATES PATENT OFFICE.

WILLIAM SHERMER AND SAMUEL HERMANN, OF PHILADELPHIA, PENNSYLVANIA.

TOOTH PROTECTOR.

Application filed December 5, 1924. Serial No. 754,040.

To all whom it may concern:

Be it known that we, WILLIAM SHERMER and SAMUEL HERMANN, citizens of the United States, residing at Philadelphia, county of Philadelphia, and State of Pennsylvania, have invented certain new and useful Improvements in Teeth Protectors, of which the following is a specification.

Our invention relates to teeth protectors
10 for pipe stems and cigar holders.

The objects are to provide means, adapted to fit over the ends of pipe stems and cigar holders, which will serve as a cushion to absorb shocks between the teeth and the stem; which will not slip on the stem while in use; which will be sanitary, and which will fit practically all types of pipe stems and cigar holders.

These objects, and other advantageous ends which will be described hereinafter, we attain in the following manner, reference being had to the accompanying drawing in which—

Figure 1 is a perspective view of a pipe
25 having our protector applied thereto,

Figure 2 an enlarged section through the protector shown in Figure 1, showing the pipe stem broken away, and

Figure 3 a view similar to Figure 2 showing a modified form of protector.

Referring to the drawings, 1 indicates a pipe, 2 its stem and 3 a shoulder adjacent the end of the stem. For purpose of illustration, we have shown our protector applied to a pipe stem but it may be used equally well with any cigar or cigarette holder which has a stem and a shoulder similar to the stem 2 and shoulder 3. The protector consists of a tubular part 4 which fits around the stem, a bead 5 on the end of the tubular part and abutting shoulder 3, and an enclosing part 6 on bead 5 which fits over the end of the stem. The part 6 has a hole 7 therein through which smoke is drawn from the stem. The enclosing part 6 serves the dual purpose of preventing the tubular part from slipping inwardly on the stem and as a cushion to absorb shocks when the end of the stem strikes against the teeth. The bead 5, abutting shoulder 3, prevents the protector from slipping off the stem and serves as a cushion to absorb shocks when the shoulder strikes

against the inner side of the teeth. The bead also serves as a shoulder for preventing the stem from slipping from between the teeth. Part 6 on bead 5 prevents foreign matter from lodging between the bead and the shoulder, and makes the pipe sanitary. The protector may be made of suitable elastic material such as rubber.

In Figure 3, I have shown a tubular part 4^a, and a bead 5^a on the tubular part abutting the shoulder 3 on the stem 2. A protector of this form is simple and may be made at low cost.

While we have described our invention as taking a particular form, it will be understood that the various parts may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. A tooth protector for pipe stems and cigar holders having a stem and a shoulder thereon, and consisting of a tubular part adapted to fit around the stem, a bead on one end of the tubular part adapted to abut the inward side of the shoulder, and an enclosing part extending outward of the bead adapted to fit over said shoulder and the end of said stem and having an opening therein for passage of smoke from the stem.

2. A tooth protector of elastic anti-slipping material for pipe stems and cigar holders having a stem and a shoulder thereon, consisting of a tubular part adapted to fit around the stem and having a bead adapted to abut the shoulder, and an enclosing part on the tubular part adapted to fit over the end of the stem and having a hole therein.

In testimony whereof we have signed our names to this specification in the presence of two subscribing witnesses.

WILLIAM SHERMER.
SAMUEL HERMANN.
